JACK ATTACHMENT

Filed March 19, 1926

2 Sheets-Sheet 2

WITNESS:

UNITED STATES PATENT OFFICE.

CHARLES E. SMALLEY, OF WAGNER, SOUTH DAKOTA.

JACK ATTACHMENT.

Application filed March 19, 1926. Serial No. 96,005.

This invention relates to an attachment for a twin jack, the general object of the invention being to provide means for converting a jack into a rear axle overhauling stand so that the rear ends of motor vehicles and the like can be handled by one man, thus eliminating the services of a helper.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a plan view of a jack equipped with my invention and showing it in use.

Figure 2 is an elevation of Figure 1.

Figure 3 is a section on line 3—3 of Figure 1.

Figure 4 is a section on line 4—4 of Figure 2.

In these views, A indicates the twin jack which may be of any desired type and 1 indicates a beam which has a channel 2 at one end thereof for engaging a part of the frame of the jack and a bearing plate 3 at its other end which engages the top part of the frame of the jack above the third wheel thereof. The middle part of the beam curves downwardly so that its rear part is below the plane of the front part, as shown in Figure 2. This will enable the beam to be placed on the frame of the jack with its channel or hook part 2 engaging the rear bar of the frame of the jack and its bearing plate 3 resting upon the top of the frame above the third wheel thereof. This will support the beam on the jack.

The front end of the beam 1 is provided with a pair of bearings 4 for a shaft 5 which has a T coupling 6 at its outer end which engages the threaded end of a casing 7 for a screw shaft 8, a hand wheel 9 having a threaded hub engaging the shaft and resting upon the coupling, these parts forming a jack for supporting the front end of the jack shaft housing a of a motor vehicle.

A collar 10 is fastened to the shaft 5, between the bearings 4, by a set screw and a spring 11 is carried by the shaft and bears against the collar and the rear bearing 4. This spring tends to hold the shaft 5 in

its forward position and with a pin 12 in the end of the shaft in engagement with any one of a number of notches 13 formed in the rear end of the rear collar 4. This arrangement will hold the shaft against rotary movement with the jack in either upright position or in a horizontal position. When in a horizontal position, the said jack, which includes the casing 7 and the shaft 8, can be passed under a motor vehicle and then, by pushing the shaft 5 rearwardly to free the pin 12 from one of the notches 13, the said jack can be moved to a vertical position and it will be held in this position by the pin 12 engaging the vertical notch 13. By turning the wheel 9, the shaft 8 of the jack can be adjusted to hold the jack shaft and its casing in the desired position.

A stationary member 14 of a clamp is fastened to one of the jacks of the twin jack by the bolts 15 so that this member 14 becomes a part of the twin jack. The other part 16 of the clamp is hingedly connected with the part 14 by having a hook-shaped projection 17 thereon engaging a hole in an extension 18 of the part 14 and the parts are removably held in clamping relation by means of a long T bolt 19 passing through the extensions 20 which are opposite the hinge of the clamp and the nut 21 having a handle 22.

From the foregoing, it will be seen that the clamp, composed of the parts 14 and 16, can be used for clamping the rear axle housing of a motor vehicle to the twin jack so that the rear end assembly of a vehicle can be fastened to the jack, with the jack shaft and its housing in either horizontal, inclined or vertical position so that the various parts can be placed in the most suitable position for working upon them.

As before stated, the jack carried by the attachment, is useful for holding the jack shaft housing in its proper position for enabling one man to reassemble the universal joint parts of the vehicle.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. An attachment for a jack comprising a

supporting beam, means for detachably connecting it with the frame of a jack, a shaft 5 slidably and rotatably connected with the supporting beam, a jack carried by the shaft and spring latch means for holding the shaft in a position with the second jack in either vertical position or in a horizontal position.

2. An attachment for a jack comprising 10 a supporting beam, means for connecting it with the frame of a jack, a pair of bearing parts at the front end of the beam, a

shaft slidably and rotatably supported in said bearing parts, a jack carried by the shaft, one bearing part having a plurality 15 of notches therein, a pin on the shaft for engaging any one of the notches, a collar on the shaft and a spring pressing against the same and one of the bearing parts for yieldingly holding the pin in any one of the 20 notches.

In testimony whereof I affix my signature.

CHARLES E. SMALLEY.
